Patented Jan. 7, 1919.

UNITED STATES PATENT OFFICE.

FRITZ ARTHUR ANDERSON, OF MILTON, WISCONSIN, ASSIGNOR TO BURDICK CABINET CO., OF MILTON, WISCONSIN, A CORPORATION OF WISCONSIN.

TERAPEUTIC APPARATUS.

1,290,036.

Specification of Letters Patent.

Patented Jan. 7, 1919.

Application filed March 4, 1918. Serial No. 220,258.

To all whom it may concern:

Be it known that I, FRITZ ARTHUR ANDERSON, a citizen of the United States of America, and a resident of Milton, county 5 of Rock, and State of Wisconsin, have invented certain new and useful Improvements in Therapeutic Apparatus, of which the following is a specification.

This invention relates to a supporting 10 structure for the casings of heating and lighting devices intended for therapeutical use. The main objects of the invention are to obtain certain desired vertical and angular 15 adjustments of the casing by means of a light and rigid structure; and to make such structure foldable into compact relation with the casing so that the device may be conveniently carried or shipped.

An illustrative embodiment of this invention is shown in the accompanying drawings, in which—

Figure 1 is a perspective view of a casing and supporting structure therefor constructed according to this invention.

Fig. 2 is a perspective view showing the supporting structure in folded relation with respect to the casing.

Figs. 3 and 4 are details of the joint between the yoke and standard.

Devices of the general class to which this invention relates may be employed as electrical heaters for general use, as well as for therapeutic purposes. In the latter use of the device, the heat and light may be regulated to the desired degree of mildness by cutting out of circuit a number of the resistance lamps which are usually mounted in the casing and provide the necessary heat and light. The effect of the heat and light 30 on the patient may be further regulated by an angular adjustment of the casing or by moving it toward or away from the patient. These adjustments also facilitate the use of the device for local applications when the patient is in sitting or lying position.

The legs of the supporting structure in the present device may rest on each side of a bed or cot so that the casing is directly over the patient. The casing may then be adjusted vertically or around its pivot.

The structure shown comprises a pair of standards or legs 1 of triangular form as shown in Fig. 1. The upper ends of the standards fit within recesses 2 in the lower 55 ends of an inverted U-shaped member or

yoke 3 which serves to rigidly connect the standards. The latter are pivoted by pins 4 to the yoke and the recesses 2 are so formed as to permit the standards to be folded inwardly underneath the supported casing 5, 60 but to prevent the standards from being swung outwardly beyond a position slightly past a vertical position whereby they will securely support the casing when set up. The upper end of the yoke is formed to provide an aperture or guideway 6 in which is slidably mounted the shank 7 of a handle 8. The shank 7 is pivoted at its lower end by the flush headed pin 9 to a short arm 10 rigid with the casing 5. This arm 10 is of 65 the same cross section as the shank 7 and may accordingly pass through the aperture 6 in the yoke 3, as shown in Fig. 2. A flat-headed thumb screw 11 is threaded into the yoke 3 in position to clamp the shank 7 or 70 the arm 10 to the yoke. With this arrangement, the casing 5 may be secured in its different positions with respect to the standards. Angular adjustment of the casing 75 around the pivot 9 may be effected by means of a chain 12 secured at one end to an eye 13 fast to the casing and arranged to slide through an aperture or guideway 14 in the handle 8. A small pin or hook 15 is rigid with the handle and serves as a fastening 80 means for the chain 12.

In the operation of the device, the vertical adjustment of the casing 5 is effected by pulling the handle 8 upwardly and locking it in set position by means of the screw 11. 90 Angular adjustment is effected by pulling the chain 12 through the aperture 14, and passing a link of the chain over the pin 15.

When the device is not in use or is to be transported, the supporting structure is folded against the casing as shown in Fig. 2. This is effected by first drawing the handle upwardly until the arm 10 of the casing extends through the aperture 6 in the yoke. The casing may be clamped in this position 100 by means of the screw 11 and then the legs or standards 1 are folded inwardly and the handle 8 is swung downwardly against the casing.

In order to be able to lock the legs 1 positively either in their extended or folded positions each leg 1 is provided with a spring actuated detent 16, which has a shank extending through the adjacent part of the leg 1 and through arcuate slots 17 in the cheek 110

pieces of the socket member 2. The slot in one side of the socket member is enlarged at its ends to provide recesses 18 in which the enlarged head of the detent 16 may be seated to lock the joint, as will appear from Figs. 3 and 4. In order to unlock the joint the cap 19 is pressed inward until the head of the detent is pushed out of the respective recess 18, whereupon the leg may be swung 10 to its other position where it will be again locked by the detent under the action of the spring 20.

When it is desired to treat a larger area of the patient's body than is covered by the 15 casing of the small sized device herein shown, or when the apparatus is to be used to perform the functions of a heat and light bath cabinet, two of these devices may be placed end to end and a blanket thrown over 20 them and supported by their standards.

Although but one specific embodiment of this invention has been herein shown and described, it will be understood that numerous details of the construction shown may 25 be altered or omitted without departing from the spirit of this invention as defined by the following claims.

I claim:

1. In a device of the class described, the 30 combination with a casing for heating or lighting elements of a supporting structure therefor comprising a pair of standards connected by a yoke at their upper ends, and a shank slidably mounted in said yoke, said 35 shank being pivoted at its lower end to said casing.

2. In a device of the class described, the 40 combination with a casing for heating or lighting elements of a supporting structure therefor comprising a pair of standards connected by a yoke at their upper ends, a shank slidably mounted in said yoke, said shank being pivoted at its lower end to said casing, and means for clamping said shank to 45 said yoke.

3. In a device of the class described, the 50 combination with a casing for heating or lighting elements of a supporting structure therefor comprising a pair of standards connected by a yoke at their upper ends, and

a shank slidably mounted in said yoke, said shank being pivoted at its lower end to said casing, said standards being pivotally connected to the yoke whereby they may be folded inwardly underneath the casing. 55

4. In a device of the class described, the combination with a casing for heating or lighting elements of a supporting structure therefor comprising a pair of standards connected by a yoke at their upper ends, a 60 shank slidably mounted in said yoke, said shank being pivoted at its lower end to said casing, and means for rocking the casing around its pivotal connection with said handle and securing the casing in its moved 65 position.

5. In a device of the class described, the combination with a casing for heating or lighting elements, of a support arched over 70 said casing, an arm rigidly secured to said casing, a shank pivotally connected to said arm, and a guideway in said yoke for receiving said shank and through which the shank and said arm are slidable.

6. In a device of the class described, the combination with a casing for heating or lighting elements, of a support arched over 75 said casing, an arm rigidly secured to said casing, a shank pivotally connected to said arm, a guideway in said yoke for receiving 80 said shank and through which the shank and said arm are slidable, and means for adjusting said casing to different angular positions relative to said shank.

7. In a device of the class described, the combination with a casing for heating or lighting elements, of a support arched over 85 said casing, an arm rigidly secured to said casing, a shank pivotally connected to said arm, a guideway in said yoke for receiving 90 said shank and through which the shank and said arm are slidable, a chain secured to said casing at one side of said shank, guiding means on said shank for said chain, and means for securing said chain to said shank for adjusting the angular position of 95 said casing.

Signed at Milton this 19th day of Feby., 1918.

FRITZ ARTHUR ANDERSON.
